UNITED STATES PATENT OFFICE.

WILLIAM A. WATSON, OF MEDFORD HILLSIDE, MASSACHUSETTS, ASSIGNOR TO NATIONAL PIANO COMPANY, OF BOSTON, MASSACHUSETTS, A CORPORATION OF MAINE.

PNEUMATIC ATTACHMENT FOR PIANOS.

1,059,324.

Specification of Letters Patent. Patented Apr. 15, 1913.

Application filed September 8, 1905. Serial No. 277,490.

To all whom it may concern:

Be it known that I, WILLIAM ARTHUR WATSON, of Medford Hillside, in the county of Middlesex and State of Massachusetts, have invented certain new and useful Improvements in Pneumatic Attachments for Pianos, of which the following is a specification.

This invention relates primarily to pianos and other musical instruments in which mechanism may be combined to convert such instruments into self-playing instruments, and my invention relates particularly to that class of pneumatic pianos in which the mechanism is contained entirely within the piano-case.

The primary object of the invention is to provide an attachment for the automatic playing of pianos, which attachment is contained within the case of the piano and is out of sight, but which is readily removable for the purpose of inspection or repairs, and which may be employed in any piano of ordinary construction, the said attachment being so compact that it does not interfere with the operation of the piano action or other parts of the instrument. The compactness of the attachment and the general structure is of such a character as not to interfere with the freedom of tone, that is, obstruct the passage of sound waves from the piano to the room.

Another object of the invention is to construct the attachment in several parts, or units which may be individually or independently removed from the piano for the purpose of inspection and repair of either of the parts of the attachment or of the piano itself, thereby rendering it unnecessary to remove further parts of the mechanism than may be required to furnish access to the particular part needing attention.

Other objects of the invention are to improve and simplify various parts of the mechanism needed to convert an ordinary piano into a so called self-playing piano, and render such parts more diminutive in appearance and consequently more in keeping with the present style of piano construction, all as will be more fully herein-after described and pointed out in the claims.

In carrying out my invention I not only utilize the spaces existing in pianos where

the mechanism can be conveniently placed, but I also place and arrange the parts of my attachment without apparent increase in the mechanism of the piano as a whole, giving it the appearance of a simple extension of the present mechanism. The result of this is that there is little or no confusion to repairers, because of the presence of the parts of the attachment, and also the sound vibrations emanating from the piano are allowed entire freedom.

Other objects of my invention are to provide improvements in an organized piano of this character which result in advantages that will be more fully explained herein-after.

To these ends my invention consists in the construction and combination of parts substantially as hereinafter described and claimed.

Of the accompanying drawings:—Figure 1 represents a vertical section through a complete instrument embodying my invention. Fig. 2 represents a front elevation of the same the right hand portion being broken away and portions being broken out at the upper left hand parts of the figure to show interior details of construction. Fig. 3 represents an elevation of a rear portion of the frame or so-called skeleton back of the piano to which the bellows are attached, said frame or skeleton back being removed from the case. Fig. 4 represents a section on line 4—4 of Fig. 3. Fig. 5 represents an enlarged section on line 5—5 of Fig. 1. Fig. 6 is a perspective view of the air trunk brackets. Fig. 7 represents an elevation of the same, partly broken out and in section. Fig. 8 represents a section on line 8—8 of Fig. 7. Fig. 9 represents a detail section, enlarged, on line 9—9 of Fig. 2. Fig. 10 is a view similar to the lower portion of Fig. 9, the lower pneumatic being collapsed. Fig. 11 is a detail plan view, enlarged, of one of the coupler tongues. Figs. 12 and 13 are views similar to portions of Fig. 1, showing two of the removable units detached. Fig. 14 represents a detail, enlarged from Fig. 1, of the means for holding the coupler tongues projected or retracted. Fig. 15 represents a detail section on line 15—15 of Fig. 1. Figs. 16, 17, and 18 represent respectively detail sections on lines 16—16, 17—17, and 18—18 of Fig. 9.

Similar reference characters indicate the same or similar parts throughout the several views.

Such parts of the casing and frame and details of the piano itself as are illustrated in the drawings are or may be of any ordinary or preferred type. It will not be necessary herein to describe or even mention many of the parts of the piano itself, and it will be sufficient to refer to the frame or plate 20, the strings 21, the sounding-board 22, the piano action as a whole indicated at 23, the key-bottom 24 and the key-frame 25.

The key-bottom 24 is cut away at the rear as indicated at Fig. 1; that is, it is of much less depth than in the ordinary piano. This provides space for the pneumatic units of the attachment, and at the same time provides less obstruction for the passage of sound waves from the piano. Each key 26 is preferably formed with a recess or mouth 27 at its rear end to provide for the engagement of a coupling device to give motion to the keys whenever desired. Otherwise each key is constructed and mounted substantially as in an ordinary piano. Therefore a series of tongues 28, one for each key, is pivoted at 29 (Fig. 13) to the rail 30 and the front end of each tongue enters the mouth or recess 27 (Fig. 1) of a key. The rail 30 is hinged at 31 to a suitable strip or bar that is carried by the pneumatic unit, and said rail is provided with an upwardly projecting arm 32 at one end, said arm having its upper end engaged with the under surface of a cam spring 33 (Fig. 14) consisting of an undulating piece of resilient metal secured at its ends to the bracket 34. Said spring is formed with two depressed portions as best shown in Fig. 14 so that when the arm 32 is in one or the other of the depressed portions the rail 30 will be held backward sufficiently to discharge all of the tongues 28 from the keys, in which case the pneumatics will actuate the action independently of the keys, or, as shown in Fig. 1, in which the tongues 28 are in engagement with the keys, the movement of the pneumatics to actuate the hammers will also actuate the keys. From this it will be readily understood that (1) the keys may actuate the action irrespective of the pneumatics; (2) that by a disengagement of the tongues 28, the action may be actuated by the pneumatics without affecting or operating the keys, and (3) the engagement of tongues 28 and the keys will cause the keys to be actuated by the pneumatics. In other words, the independent abstracts 38 and capstans 39 provide independent means, operated respectively by the keys and the pneumatics, for actuating the action, the tongues 28 forming connecting means for the pneumatic devices and the keys when the automatic operation of the latter is desired. As

a means for swinging the rail 30 in the manner described, I prefer to provide a clip 35 (Fig. 12) having spring-jaws adapted to engage an offset portion of the arm 32, said clip 35 having a forwardly extending portion or rod 37 terminating in a handle or knob 36 (Fig. 12) that is within easy reach of a person at the front of the instrument when the cover is raised. Any suitable means may be provided for supporting and guiding the rod 37. The reason for constructing the clip 35 with spring-jaws is to enable the same to be readily detached from the portion of the arm 32 which is engaged by said clip when the unit illustrated in Fig. 12 is to be removed from the instrument, as will be hereinafter described.

Two sticker-operating devices comprising the abstract 38 and capstan 39 are shown as adapted to engage the sticker 40 of the piano action. Said sticker 40 has a widened foot as shown in Fig. 1, said foot being engaged by both said abstract and capstan. The capstan 39 is carried by a key 26 while the abstract 38 is longer and extends down in position to engage the upper lever 55 of the pneumatics, as shown in Figs. 1, 9 and 13. As shown in Fig. 11 each tongue 28 is slotted as at 42, the abstract 38 passing through said slot and provided with regulating buttons 41 above and below the tongue, whereby the engagement is such between each tongue 28 and capstan 39 that when the parts are in the positions shown in Fig. 1 the keys, which otherwise would be motionless are made to move. When the key-bottom, key-frame, keys, cover, key-blocks and lock-rail are all removed as shown in Fig. 12, unlimited access is afforded to every part of the piano and pneumatic actions, and to the plate, strings, sound-board, pedals, and treadle mechanism, and there will still remain a connection between the pneumatics and the stickers 40 of the piano action so that the piano may be played during the inspection of parts notwithstanding this dissection.

In Fig. 1, 43 represents one of the supporting guides which supports one end of the key-bottom 24, and the parts superposed thereon, screws 44 passing through the guides 43 into the said key-bottom and the end blocks thereof. When the screws 44 are removed, the key-bottom 24, key-frame 25 and the keys 26 and the cover of the keyboard, (all of these parts being represented in Fig. 12, as a unit,) may be readily drawn out from the piano-casing, the mouths or recesses 27 of the keys readily leaving the tongues 28, and the clip 35 separating from the arm 32. At the same time the key-frame draws away from its rear supporting guides 46 (Fig. 13).

The pneumatics are for convenience arranged in two banks or horizontal rows, one

above the other, alternate keys being operatively connected to adjacent pneumatics of the same bank, each pneumatic being of such size and proportion as to contain the proper 5 volume of air necessary for the desired action for the operation of the piano, in the manner hereinafter referred to. As best shown in Fig. 9, the two banks of pneumatics and their appurtenances are alined 10 by brackets, one of which is shown in said figure at 45. Each of said brackets comprises upper and lower substantially horizontal portions and a vertical portion or web connecting them, the left hand edge of 15 the bracket being open. The objects of this construction are manifold, being not only to hold in proper alinement all of the parts superposed thereon, but to afford an easy dissection of the brackets, pneumatic levers 20 55 and their appurtenances from the pneumatic banks, by the removal of the screws 50. Each bracket is formed with an opening 25 to provide a handle 46 and is also provided with pendant ends or feet upon which to stand when removed from the piano casting, and with flanges 47 to which the upper and lower tube-boards 48, 49 are secured by screws 50. As shown in Fig. 9 the vertical portions of each bracket 45 project beyond 30 the plane of the rear ends of the pneumatics 51 and also beyond the plane of the rear edges of the links 54. Therefore the brackets 45 and the two banks of pneumatics and the primaries, when removed from the piano 35 as a unit, may be turned over so that the portions of the brackets which connect the upper and lower arms may rest on the floor, without risk of damage to either the pneumatics or the said links. The handles 46 40 have their top and front edges so formed as to constitute suitable guides for the key frame when the latter is introduced to position, and to support said frame when so placed. The rear edges of said tube-boards 45 are also secured to the vertical portions of 45 the brackets 45 by similar screws 50, and at this point act as guards to protect the sticklers from injury by a slight non-alinement. The two tube-boards 48, 49 are substantially 50 identical and are formed with the tubes, ducts, or windways as hereinafter described. Each pneumatic 51 of the two banks is detachably secured under its respective tube-board 48 or 49, as by ribs projecting inwardly 55 from the primary shells 57 into dove-tailed ways or grooves 92 formed in the upper member of each pneumatic. Similar to the ribs, projecting from the primary shells, as before mentioned, and attached 60 to the lower side of the tube-board, are also suitable extension guides for the better support of the rear extended portion of the pneumatics. As indicated in Fig. 9, the upper levers 55 extend over a rear portion 65 of the upper tube board 48, which por-

tion is preferably provided with a felt cushioning strip as at 550. This provides a rest or support for preserving the alinement of the upper levers 55 and owing to the links 54, also preserves the alinement of the movable portions of both banks or series of pneumatics when at rest, because the movable members of the upper and lower pneumatics are connected to the said links by the toes 52. The reason for making each pneumatic relatively long and narrow is to provide normal capacity for power while reducing to the minimum the number of banks of pneumatics; and to this end all of the space available from the strings out, is utilized, reducing the iron plate also to nearly or quite the same plane as that of the strings, providing, of course, for an equal strengthening of the plate in a lateral direction. This arrangement also provides important advantages in leverage-power in addition to pneumatic-power already alluded to, which will be hereinafter more fully described. The movable member of each pneumatic is provided with a toe or projection 50 90 52, adapted to enter a hole 53 formed in a stickier or lifter link 54, so that when the pneumatic is removed from its guides the toe is drawn away and is disengaged from the lifter link, the toe being free to be withdrawn by such removal of the pneumatic. By this construction, in addition to dispensing with any necessity for manipulating a connection between the toe and lifter, there is a mutual co-action between the toe and 95 lifter to prevent any appreciable relative lateral movement of the pneumatic and lifter, the toe thereby forming a guide for the lifter 54. The link 54 has its upper and lower ends pivotally connected with the 100 outer ends of upper and lower levers 55 pivotally at 56 to suitable fixed points of the frame of the pneumatic unit. All of the links 54 are arranged vertically in alinement, or in other words side by side, and the 105 levers 55 of each row are arranged in parallelism, the pivots of each pair of the levers 55 being one above the other and substantially alined with the ends of their respective pneumatics. The levers 55 are substantially of the same length as the movable members of the pneumatics and the pivot points at one end thereof are in substantial vertical alinement with the pivot of the keys, therefore reducing to a minimum all 110 friction of the moving parts, also affording absolute uniformity of movement, and further permitting the upper levers 55 to engage with the lifters or abstracts 38 at points remote from the free ends of the levers, 115 120 thereby increasing the leverage of the movable members of the pneumatics. 125

The summary of the preceding description attaches importance to the location and proportion of the pneumatics, viz. an unusual 130

- extension toward the strings for the promotion of leverage; a contra extension to locate their pivotal points under the key fulcrum; a forward and backward extension 5 combined with proper width to produce power capacity; and a narrow width so as to reduce the number of pneumatic banks within the range of the width of the piano action.
- 10 Each tube-board is formed with a so-called chamber b running its entire length in which chamber the air is under tension or partial vacuum as will be hereinafter described. And each tube-board is formed 15 with ducts or windways a' and a^2 , connected by curved tubes a^2 , as shown in Fig. 8. In Figs. 9 and 10 the tubes a^2 are omitted from most of the ducts a^2 for the sake of clearness of illustration, but it will be understood 20 that, in practice, tubes a^2 connect all of the ducts a' and a^2 . The ducts a' extend under the vacuum chamber b and of course there will be one of such ducts for each piano key. In each tube-board there will 25 be one half as many ducts a' as there are keys, the other half of the ducts being in the other tube-board. Secured against the front edge of each tube-board is a series of primary shells 57, one for each duct a' and 30 communicating with such duct a' through a port or passage a . The port a is formed in the lower part of the shell 57 and removable therewith, the material surrounding the terminal of the port being flat to receive the 35 lower member of the primary. The flat face surrounding the terminal of the port may be termed a conduit-block. Each shell 57 also has a chamber for the primary or bellows 58 the interior of which communicates with 40 the port a . The upper or movable member of each primary 58 is formed with a pin-hole 59, and is provided with a stem 60 having a valve 61 the upper face of which is adapted to close openings 62 in the upper 45 wall of the primary shell, and the lower portion of said valve being adapted to control an opening c leading to a port or passage-way c' formed in the shell 57. Said port or passage-way c' connects with the 50 interior c^2 of a pneumatic 51. As will be readily understood, all of the operating parts comprised in the primary and the valves operated thereby are carried by the primary shell and removable therewith as a 55 unitary structure. And as the several compartments containing these operating parts are open on one side when the shell is removed, an inspection of this mechanism, as an entirety, is readily obtained without the 60 necessity of disturbing the position of any of the parts carried by said shell. These letters of reference will be used hereinafter to describe the course of the air, but it may be stated here that the openings 62 communicate with the atmosphere so that when

the parts are in the position shown in Fig. 9 the pneumatic 51 will be open to the atmosphere and consequently expanded as shown. As has been stated, the air in the chamber b is under tension and therefore, whenever air is admitted to one of the primaries 58 through the port a and the ducts a' , a^2 , a^3 , due to the passage of the perforation of the record sheet, the pressure of the air so admitted to the primary 58 will cause the valve 61 to lift to the position shown in Fig. 10 because the small hole 59 is not large enough to permit the air to pass through the primary 58 without actuating its movable member and valve stem and valve. As such movement of the valve opens the passage c , the air in the space c^2 of the pneumatic 51 is immediately exhausted into the chamber b , resulting in the actuation of the sticker 54 and, through the upper lever 55, the abstract 38 and the particular string of the piano designed to be sounded. As soon as the record sheet has passed so that no further air can be drawn through the ducts a' , a^2 , a^3 , the pressure of the atmosphere through the openings 62 causes the valve to fall from the position shown in Fig. 10 to that shown in Fig. 9, the air that is in the primary 58 now escaping through the pin-hole 59. Air under atmospheric pressure then immediately passes through the passageway c' into the space c^2 of the pneumatic and causes the pneumatic and the stickers to return to the position indicated in Fig. 9.

As has been described, the banks of pneumatics represented in Figs. 9 and 10, and the several brackets 45 which comprise the alining frame of said banks, are removable from the casing. The line of separation of the tube-boards, so as to permit such removal of the banks, is indicated at 63 in Figs. 6 and 7. As shown in said figures portions of the tube board in which the air ducts or windways are formed overlap. That is, at each end of the removed unit, portions of the action extend over and rest upon brackets or fixed members within the casing in which continuations of the air ducts or windways are formed. The horizontal portion of the fixed bracket is represented at 64 and the upright portion at 65. While Fig. 2 shows these brackets only at the left, it is to be understood that a similar structure exists at the right, and hereinafter they will be referred to as air trunk brackets to distinguish them from the metal brackets which aline the tube boards.

I shall now describe the connections and means whereby the air is kept under tension or partial vacuum in the chamber b .

The upper and lower chambers b connect with a vertical flue b' (Fig. 6) communicating with a flue or passage b^2 formed in the horizontal portion of the trunk above the

ducts a^4 (Fig. 7). Said passage b^2 communicates with a chamber b^3 and through an opening in the trunk, with passages b^4 , b^5 and b^6 (Fig. 1). It is to be understood of course that such passages or flues may exist in each end of the casing of the piano. The passages b^6 communicate with a passage b^7 (Figs. 3, 4 and 5) and the passage b^7 communicates with the spaces b^8 and b^9 in the 10 reservoir bellows 68 and the two pumping or treadle-operated bellows 69. Of course, since all of the chambers or passages from b to b^7 inclusive communicate freely with the reservoir b^8 , said chambers or passages may 15 also be construed as portions of the reservoir for the air under tension. A spring 70 located within the bellows 68 controls the amount of tension or vacuum obtained in the reservoir, the bellows of the reservoir 68 being provided with an opening covered by 20 the spring held flap 71 of an ordinary type, and the two pumping bellows 69 being formed with openings covered by spring-held flaps 72 also of an ordinary form. As 25 shown in Figs. 1, 3, 4 and 5, the bellows 68 and 69 are attached to and carried by the back-frame 73 which back-frame is removably held in place by any suitable means. When in the position shown, the air passage 30 b^7 in the back-frame 73 communicates at its ends with the air passage b^8 (Fig. 5). The special novelty of this part of the invention comprises the removable back carrying a bellows device and acting as legs or a support 35 for the same whether in or out of the piano, and the said back being channeled to form a concealed conduit for the bellows, and the peculiar arrangement of the valves communicating with said bellows and channel. 40 Owing to the fact that the removable back-frame 73 extends below the extreme lower portion of the bellows attached to said back-frame, the lower portion of said frame acts as legs to support the bellows in free working position when in the piano, and will also act as legs to support the bellows free from the floor when the back is removed and 45 stood up against the wall of the room or elsewhere.

50 I shall now describe the means for operating the pumping bellows and the construction whereby the treadle-mechanism may be folded within the casing of the piano as indicated by dotted lines in Fig. 1:—The lower part of the front of the piano casing is formed with an opening 74 which opening may be closed by suitable doors or panels 75. The side members 76 of the folding frame are pivoted to brackets 77 secured inside of 55 the base of the frame, said side members 76 passing through suitable openings in the doors or panels 75. The outer ends of the side members 76 are formed with feet 78 adapted to rest upon the floor, and are connected by a crossbar 79. Each pumping bel-

lows is actuated by an elbow lever the lower arm of which is indicated at 80, passing through suitable openings in the plate 20 and sounding-board 22. Said lower arm 80 is pivoted at 81 (Figs. 1 and 5,) to stanchions of the frame of the piano, and the upper arm 82 of each elbow lever is so formed at 83 as to engage a catch 84 carried by the upper edge of the movable member of the bellows 69. Oscillation of the elbow lever 80—82 will actuate the pumping bellows 69 in a manner that will be readily understood, to exhaust air from the passage b^7 and reservoir bellows 68. The outer end of each lever arm 80 is formed with an upturned ear 85, and the outer members 86 which comprise the folding portions of the levers are pivoted at 87 to the arms 80, extending up and over the ears 85 and through the openings in the door or panel 75. The outer end of each member 86 is pivotally connected to a foot-treadle 88 by means of a link 89. The two treadles are pivoted upon the crossbar 79 of the folding frame. By referring particularly to Fig. 1 it will be readily understood that the folding frame, the treadles, and the outer member or extension 86 of the elbow lever may all be folded to the position indicated by dotted lines, the doors or panels 76 being temporarily swung outward or slid back, or removed for the purpose. The pivots 87 are in alignment with the pivots 77 when the parts are in the position shown by full lines in Fig. 1, and therefore the members 76 and 86 will readily fold up together, carrying the treadles with them. But when the feet 78 rest upon the floor, a firm foundation is afforded for the pivoted ends of the treadles and when pressure is exerted upon said treadles the links 89 bear 100 the outer members 86 of the folding lever arms downward. The upturned ears 85 of the arms 80 prevent the members 86 from turning on the pivots 87 when pressed downward, and therefore each jointed arm 80 and 105 86 moves downward as a rigid portion of the elbow lever, on the pivot 81, thereby expanding the bellows 69. To return the lever and bellows, I may employ a coil spring 91 connecting said lever with a suitable fixed part 110 such as the scale plate of the piano.

The air conduits or windways will now be described and direction of the movement of air pressure therein:—The operation of the treadles results in actuating the two pumping 115 bellows and to exhaust the air into the chamber b^9 thereof from the chamber b^8 of the reservoir bellows 68. At the same time the air is exhausted, or put under tension, to the same degree throughout the conduits or 120 passages b^7 , b^8 , (Figs. 3 and 4) b^5 , b^4 , (Fig. 1) b^3 , b^2 , (Fig. 7) b' and b (Figs. 6, 8, 9 and 10). Whenever an opening or perforation in the record sheet 66 crosses an opening a^6 in the tracker-board 90, there is an 125 130

immediate tendency of air to pass through the ducts or windways a^5 (Figs. 1, 2 and 7) and a^4, a^3, a^2, a' (Fig. 10) and a , due to the suction or exhaust in the chamber b . That is, since there is tension in chamber b , as soon as atmospheric air is admitted through the duct a , by means of the record and tracker-board as described, the primary 58 expands and shifts the valve 61 from the position shown in Fig. 9 to the position shown in Fig. 10. The resulting action has been referred to, but will be explained again by stating that this shifting of the valve instantly opens communication from the air tension of the chamber b to the selected pneumatic 51 through the opening c and the port c' leading to the space c^2 in said pneumatic. The toe 52 of such pneumatic lifts its particular link or sticker 54 and causes the upper lever 55 to actuate the abstract 38 and the particular piano-action sticker 40. The perforation or hole of the record having passed the opening in the tracker-board, atmospheric pressure is cut off from the conduits $a, a', a^2, \dots$, and the tension in the chamber b aided by atmospheric pressure upon the top of valve 61 when in the position shown in Fig. 10, causes the valve to descend to the position shown in Fig. 9, sufficient air escaping from the primary 58 through the small opening 59 to permit of the collapse of the said primary. The opening c being then closed, no further action of the particular primary 35 and pneumatic occurs until another perforation of the record passes the particular opening in the tracker-board. And the valve 61 being in lower position, atmospheric air enters through the openings 62 to the port c' and the space c^2 in the pneumatic 51 that has been actuated, so as to instantly return the link or sticker 54 and permit the abstract 38 to drop.

When it is desired to obtain access to the pneumatic action, the screws 44 (Fig. 1) are removed, and the key-bottom 24 with the parts supported thereon as shown in Fig. 12, are removed bodily from the piano-case. Then, through the opening thus provided 50 by the so-called lower panel of the case, or through any other suitable opening that may be made in the casing, the frames 45 may be grasped by the handles 46, and said frames and the banks of pneumatics carried thereby may be lifted out of the casing. Whenever it is desired to obtain access to the piano-action, it is done in the ordinary way. A preferred way of removal is by first removing the usual detachable parts of 55 the case, as in the work of tuning and regulating the instrument, when the action also is removed, after which the parts of the attachment may be more readily removed. After this last step, the key-bottom 24 and 60 the parts supported thereby may be returned

to position, and the piano may be played by its finger-keys in the usual manner, the capstans 39 serving to engage the stickers 40 of the piano-action. Or if the parts shown in Fig. 12 are removed and the parts shown in Fig. 13 left in the casing, the result is that I have provided a pneumatic piano without keys, but fully adapted to receive keys. And as has been described, the back-frame 73 and the bellows carried thereby may be removed for the purpose of inspection or repair, or to give access to the sounding-board.

It is to be understood that the bellows and treadle mechanism may be entirely dispensed with, in which case the duct or ducts b^6 (Figs. 1 and 5) may be connected with any suitable source of air under tension.

The construction of the primary shell is such as to admit of its being removed from the so-called chamber b , without disturbing any of its interior adjustments, and so disclosing its true condition, whether correct or faulty, whenever necessary. This advantage is, of course, due quite materially to the fact that the primary shells are, as shown in Figs. 9, 10, 16 and 18, seamless, or with all the walls and partitions integral, but still capable of having other parts placed therein or removed therefrom. The shell 95 may be a light metal casting, or of vulcanizable material, the essential features being that it is air tight when in position in the instrument, and shall be capable of permitting its contained parts to be removed for examination without dis-associating said parts, and it also prevents any possibility of leakage of air due to shrinkage and swelling or faulty construction liable to exist when made of separate pieces of wood glued or otherwise secured together.

As best shown in Figs. 7, 9, 10, and 16, the upper board of each pneumatic 51 is formed with dovetail ways 92, which fit corresponding ways formed in the bases of the tube-boards 48 49, whereby said pneumatics are detachably connected with said tube-boards. The lower end of each primary shell 57 is formed with ribs 93, which fit the front ends of the ways 92 of the pneumatics, so that the primary shell will be firmly held in its position relatively to its corresponding pneumatic, as shown in Figs. 9 and 10, or may be slid off from the ways 92. Each primary shell 57 is secured in operative position, to the front of its tube-board, by screws 94, said screws extending into the tube-board, and holding the shell sufficiently closely to the board to make the passages between the shell and tube-board air-tight. If desired, however, suitable packing may be employed at the joint. Owing to this construction, the primary shell may be removed for inspection or repair, independently of its pneumatic, or the pneumatic

may be removed independently of its co-operating primary shell, or the two may be removed together, all without removing the banks from the piano-casing. The pneumatic is removed by being withdrawn from its guides in the direction of its length and toward the front of its support, thereby withdrawing the toe 52 from the opening in the lifter 54 without disarranging or moving any of the parts operatively connected with the pneumatic. If necessary, the pneumatic may be collapsed during the withdrawal or re-insertion to permit of its ready passage to and from its normal position.

15 As clearly shown in Figs. 9 and 10, the air-port c' of the primary shell connects with the interior space c^2 of the pneumatic at a point very close to the hinge point of the latter. Therefore, the air in its course to 20 or from the pneumatic 51 takes a direct course instead of an angular one, such as would result from forming the connection at a point near the middle of the pneumatic. In other words, the location of the point 25 where the air passes from one member to the other, close to the hinge point of the pneumatic, avoids the presence of any considerable body of air near the hinge point, which would have to take a course to the port c' 30 in a direction opposite to the air which is in the body of the pneumatic.

Referring to Figs. 1 to 9, and 13, it will be noticed that the handles 46 present an inclined surface at 95 which serves as a 35 guide to facilitate the introduction of the unit shown in Fig. 12; that is, when the key-frame 25 and the parts connected therewith are introduced into the piano-casing, the inner end of the frame 25 will, if sufficiently raised, contact with the inclined surface 95 of the handle 46, so as to thereby 40 guide the inner edge of the key-frame to the proper plane; and further inward movement of said unit results in the inner portion of the key-frame being supported upon the horizontal upper surface of the handles 46; which are, in turn, supported by the tube-boards 48, 49.

As shown in Figs. 9 and 10, the valve 61 50 is pitted at its top and bottom, and cut away around its sides, to dispense with unnecessary weight and material for agility of motion and greater freedom of air circulation, for the promotion of sharper and more 55 rapid repetitions of movements of the parts. A stem passing through the valve and secured to the movable member of the primary, is provided with a head above the valve, and a tension-button beneath it, to admit of the parts yielding to the inequality of wear, etc. The upper end or head of said stem is made hollow, and receives a pendant stem, which acts as a perpendicular guide for the more accurate seating of the valve.

65 The air trunk brackets 65 are rigidly yet

detachably secured to the instrument by any suitable means, and constitute a second set of brackets on which the cross-piece 96 rests, as indicated in Fig. 2. To said cross-piece, the frame of the tracker-board 90 and mechanism which carries the record, is secured as by brackets 97. The air-tubes which connect the openings a^6 in the tracker-board with the tubes a^5 , are shown as also supported by the cross-piece 96. Obviously, however, the air-ducts might be formed in said cross-piece, or the cross-piece made thick enough to include the said air-ducts. The cross-piece 96 and the air-ducts and tracker-board and the record mechanism supported thereby, rests at its ends upon the tops of the vertical portions 65 of the air trunk brackets, which as before stated, practically constitute a second set of brackets, so far as concerns the function of supporting the removable cross-piece and record mechanism. It also supports the banks of pneumatics, as has already been described.

By comparing Figs. 1, 2, 6, 7, 8, 9 and 10, it will be seen that there is provided a frame which surrounds the piano action and carries the various tubes or conduits for air. The side portions of this frame comprise the vertical parts 65 which, as described, are fixed within the casing of the piano and constitute brackets which support the upper cross portion 96 which, in turn, supports the tracker board as described. The lower end portions 64 of the bracket portions 65 support the tube boards 48, 49 and the pneumatics and primary shells and their appurtenances. This frame which, as a whole, is substantially rectangular in form, carries all of the air tubes and is located in the space 100 surrounding the piano action as above described.

As will be readily understood, since the key-bottom 24 is removably supported on the guides 43 the latter afford supports or 110 bearings which are independent of the piano-action supports, no portion of the said action being supported by the key-bottom. Also the supports for the pneumatic action are entirely separate and independent from the 115 key-bottom supports and from the piano-action supports although the pneumatic and piano actions are in operative conjunction.

The usual construction of the metal scale-plate 20 of a piano is to form it with ribs or 120 fins for strengthening purposes which ribs or fins project solely at a right angle to the plane of the plate itself. In order to provide the space indicated in Fig. 1, to receive the unit represented in Fig. 13 with the 125 pneumatics sufficiently long and narrow to enable them to be grouped in two banks and still give them normal air capacity, I provide the strengthening rib or fin parallel with the plane of the plate itself, as indi- 130

cated at 98 in Fig. 15. Usually, the plate 20 has been provided with a strengthening rib projecting entirely at a right angle to the plane of the plate, to a distance or height substantially equal to the width of the rib 98; but by forming the plate with said strengthening rib or fin in the same plane as the plate 20 instead of at a right angle thereto, sufficient space is afforded for the location of the bank of pneumatics as described and shown. It is also to be pointed out that the distance of the air-passage is of unusual shortness from the chamber *b* to the pneumatic 51, and also of unusual capacity, being as it were, a simple transmission of the vacuum tension around the frontal edge of the tube-board, directly into the pneumatic, and of nearly equal width with the pneumatic beneath it, and has a direct vertical chute-like passage of normal atmosphere from the opening 62 to the pneumatic. These features are designed to promote a more instantaneous and powerful action of the movable parts. Another feature of improvement is found in the walls of the primary, which are absolutely rigid except on the lines around the edges and center, which are flexible joints or folds, with their angles bent inward, that is, toward the central portion of its cavity, the resulting effect of which is to augment their lifting power against the valve 61, as by a toggle joint action, when pressure within the primary is exerted laterally against the inner sides of said walls.

It will be noted that the removable back forms a support for the bellows when removed from the piano and stood on the floor, which support will hold the bellows at a convenient height for inspection, or for working by hand to determine the operative condition of said bellows.

I am aware that the key operating pneumatics of instruments of this character have been controlled by means of valves and diaphragms or small pneumatics located in sectional wood casings or shells, and also in sectional metallic shells. So far as I am aware, however, I am the first to provide a structure in which the entire primary shell is seamless, instead of being made up of several seamless pieces, the advantages of which have been hereinbefore described.

Having now described my invention I claim:

1. In a musical instrument, a key-bottom cut away at the rear, and a set of pneumatics mounted in the space afforded by said reduction of the key-bottom.
2. In a self-playing piano, the combination with finger-keys having capstans, of piano-action stickers having widened feet, pneumatic playing devices, abstracts actuated by said pneumatic playing devices and

both engaging the widened feet of said stickers, means being provided for operatively connecting the pneumatically-actuated abstracts and the keys when the automatic operation of the keys is desired.

3. In a self-playing piano, the combination with a removable unit including keys having recessed rear ends, of a second removable unit comprising a set of pneumatics, abstracts adapted to be actuated by said pneumatics, and tongues engaged with said abstracts and adapted to engage the recesses of the keys.

4. In a self-playing piano, the combination with a removable unit including keys having recessed rear ends, of a second removable unit comprising a set of pneumatics, abstracts adapted to be actuated by said pneumatics, tongues engaged with said abstracts and adapted to engage the recesses of the keys, and means for withdrawing the tongues from engagement with the keys while still in operative connection with the said abstracts.

5. In a self-playing piano, the combination with finger-keys having recessed rear ends, of pivotally mounted tongues entering recesses of the keys, said tongues being provided with slots, abstracts passing through said slots and having buttons above and below the tongues, and a set of pneumatics and means whereby said pneumatics may actuate said abstracts.

6. In a self-playing piano, the combination with the piano action, of a frame provided with ducts and surrounding the piano action, a tracker board, and primaries co-operating with the tracker-board and with the ducts.

7. In a self-playing piano, the combination with the piano action, of a frame provided with ducts and surrounding the piano action, and a tracker-board, and primaries co-operating with the tracker-board and with the ducts, a portion of said frame being adapted to support the rear portion of the key frame.

8. In a musical instrument, the combination with a plurality of banks of pneumatics, of a plurality of brackets secured to said banks and holding them in alinement as a unit.

9. In a musical instrument, the combination with a plurality of banks of pneumatics, of a plurality of brackets secured to said banks and holding them in alinement 120 as a unit, said brackets having handles for lifting or transporting such unit.

10. In a musical instrument, the combination with a plurality of banks of pneumatics, of a plurality of brackets secured to said banks and holding said banks as a unit with their pneumatics in alinement, said brackets having handles for lifting or

- transporting such unit, the said brackets having also base portions adapted to rest on the floor when the unit is removed.
11. In a musical instrument, the combination with a plurality of banks of pneumatics, of a plurality of brackets secured to said banks and holding said banks as a unit with their pneumatics in alinement, said brackets having portions projecting beyond the plane of the rear ends of the pneumatics, for the purpose described.
12. In a musical instrument, the combination with upper and lower banks of pneumatics, of abstracts levers for actuating said abstracts, connections between said levers and the movable members of both banks of pneumatics, and a rest or support for preserving the alinement of the said levers and the movable members of both banks of pneumatics when said levers and members are at rest.
13. A musical instrument comprising in its construction a set of pneumatics, levers pivotally supported above and below and substantially in vertical alinement with the hinged points of the movable members of the pneumatics, links connecting the free ends of the levers, connections between the pneumatics and links for actuating the latter, and connections between the upper levers and the action of said instrument.
14. A musical instrument comprising in its construction a set of pneumatics, said pneumatics being long and narrow, levers pivotally supported above and below and substantially in vertical alinement with the hinged points of the movable members of the pneumatics, links connecting the free ends of the levers, connections between the pneumatics and links for actuating the latter, and connections between the upper levers and the action of said instrument.
15. In a musical instrument, the combination with the action thereof and abstracts for actuating the same, of a set of pneumatics, upper and lower levers pivoted in vertical alinement with the pivotal point of the movable members of the pneumatics, links connecting the free ends of said levers, said links having holes, and projections from the pneumatics detachably entering said holes of the links.
16. In a pneumatic instrument, the combination with removable pneumatics, of lifters operatively connected therewith, pivotally mounted levers pivotally connected with said lifters, and an abstract for each lifter, each abstract being in operative-contact with its lever at a point remote from the ends of the lever.
17. In a mechanical musical instrument, a windway, pneumatics slidably connected with said windway, and connections between the pneumatics and the action devices of the instrument, each pneumatic being adapted to slide into registration with its coöperating parts when placed in position.
18. In a musical instrument, brackets within the instrument and removable therefrom, and a set of pneumatics removably supported on said brackets by a slidable connection, said brackets and pneumatics being removable from the instrument as a unitary structure.
19. In a musical instrument, the combination with fixed conduit sections within the instrument, of primaries, pneumatics, and air conduit sections leading to the primaries and pneumatics, the said primaries and pneumatics and their air conduit sections removably resting on the fixed conduit sections with the conduits of the sections registering.
20. In a musical instrument, the combination with brackets supported within the instrument and having conduits or ducts, of a tracker-board and a support for said tracker-board removably supported by said brackets, the ducts of the bracket registering with ducts leading from the tracker-board.
21. In a musical instrument, the combination with brackets supported within the instrument and having air ducts, of a cross piece removably supported by said brackets and carrying air-ducts, and a tracker-board and tracker-operating mechanism supported by said cross piece.
22. In a musical instrument, the combination with a sticker or lifter having a recess, of a pneumatic having a toe entering said recess to actuate the sticker, said toe being free to be withdrawn from said recess upon removal of the pneumatic from its normal position.
23. A self-playing piano having its scale-plate provided with an integral strengthening fin in a plane parallel with the plane of the plate, and pneumatics mounted in front of the plate and close to the outer face of said fin.
24. A self-playing piano having its scale-plate provided with a widened laterally extending strengthening fin, and banks of pneumatics mounted in front of the plate and close to the outer face of said fin.
25. In a musical instrument, the combination with a pneumatic having its air-port close to its hinge, of a shell containing a primary and having an opening leading to and communicating with the air-port of the pneumatic, said shell forming a portion of the support for the pneumatic and removable independently thereof.
26. In a musical instrument, the combination with a suitable support, of a detachable primary shell and a detachable pneumatic, a port leading through said primary shell from the pneumatic to the support, said shell and pneumatic being detachable independently of each other.

27. In an automatic musical instrument, a partitioned casing or shell, a valve and a valve-operating pneumatic located in chambers in said casing, said parts being combined to form a detachable element which may be removed without disturbing the relationship of said valve and pneumatic, the said casing or shell having an opening to expose its interior when the casing is removed from normal or operative position.
28. In a musical instrument, the combination with a support having an air-duct or windway, of a metal primary shell having compartments for the pneumatically operated valve mechanism and detachably secured to said support and having a perpendicular duct, said compartments being open at one side to expose said valve mechanism when the shell is removed, and a pneumatic slidably connected with the support and communicating with said duct.
29. A shell for the control valve of the power pneumatic of a musical instrument, said shell having an end wall and top, bottom and side walls, all of which are seamless, the other end being open to register with a vacuum passage or chamber of the instrument, said shell also having means for holding a pneumatic and a valve in proper relative positions.
30. A shell for the control valve of the power pneumatic of a musical instrument, said shell having an end wall and top, bottom and side walls, all of which are seamless, the other end being open to register with a vacuum passage or chamber of the instrument, said shell having a partition to form a valve chamber.
31. A shell for the control valve of the power pneumatic of a musical instrument, said shell having an end wall and top, bottom and side walls, all of which are seamless, the other end being open to register with a vacuum passage or chamber of the instrument, said shell having an angular partition to form a valve chamber and a passage adapted to register with a pneumatic.
32. The combination with a shell for the control valve of the power pneumatic of a musical instrument, said shell having an end wall and top, bottom and side walls, all of which are seamless, the other end being open to register with a vacuum passage or chamber of the instrument, said shell having a partition provided with a port, of a valve for said port, said valve being located one side of said partition, and a pneumatic the other side of said partition to actuate said valve.

In testimony whereof I have affixed my signature, in presence of two witnesses.

WILLIAM A. WATSON.
